UNITED STATES PATENT OFFICE.

CYRUS NORWOOD, OF WINTERS, CALIFORNIA.

GALVANIC BELT.

SPECIFICATION forming part of Letters Patent No. 224,717, dated February 17, 1880.

Application filed September 19, 1879.

To all whom it may concern:

Be it known that I, CYRUS NORWOOD, of Winters, in the county of Yolo and State of California, have invented a new and Improved 5 Electric Belt, of which the following is a specification.

My improvements relate to electric or galvanic belts to be worn upon the person for the purpose of allaying pain and preventing and 10 curing various forms of disease.

Figure 1 is an elevation, showing the inner side of the belt, partially broken open to show the construction. Fig. 2 is an elevation, showing the back of the belt. Fig. 3 shows one of 15 the zinc thimbles detached.

Similar letters of reference indicate corresponding parts.

The belt A is made of numerous short tubes or thimbles, *a*, of zinc, strung upon the copper 20 wires *b*, that pass through the tubes *a* alternately in opposite directions, so that the tubes *a* are held in place parallel with each other throughout the length of the belt. A hook-ended loop, *c*, serves to connect the ends of 25 the belt together.

The zinc tubes or thimbles *a* are formed with slots at the inner side to give access to the wire for damping with vinegar or other acid. The wires *b* are each composed of braided or 30 twisted strands, and form an endless chain at the upper and lower edge of the belt. Attached to the wires *b* is a woolen or cotton cord, *d*, which forms the belt-edge, prevents contact of the wire with the skin, and modifies 35 the electric action.

By the above-described construction only the zinc portions of the belt come in contact with the body, and the irritation caused by

contact of copper or other metals is thereby avoided.

For special cases, such as local pains in the back, breast, or elsewhere, the rosette *B* is made use of, attached to the belt *A* in the manner shown. This rosette is constructed of radial zinc tubes *a'*, strung upon copper wires 40 in the same manner as the tubes of the belt, and fitted with an edge cord, *d'*. At the central portion of the rosette the copper wires project as loops *e*, which to make contact with the copper wires of the belt are inserted in the 45 loops *f*, that are formed by wires *b* projecting through tube *a*. To retain the rosette in place loops *e f* together. 50

In use the rosette *B* will be placed directly 55 upon the affected part and the electrical effect will be concentrated by the rosette upon that portion of the body. It is intended for temporary use, and should be removed from the belt after the local pain is subdued or the desired effect accomplished. 60

The loop *c* may be caught into any one of the thimbles *a*, according to the size of belt required, and the circuit will be complete.

Having thus described my invention, I 65 claim as new and desire to secure by Letters Patent—

In combination with the belt *A*, formed with loops *f*, the rosette *B*, formed with the loops *e*, substantially as described and shown, and 70 for the purposes set forth.

CYRUS NORWOOD.
